UNITED STATES PATENT OFFICE

WERNER H. A. GUBITZ, OF DETROIT, MICHIGAN, ASSIGNOR TO PACKARD MOTOR CAR COMPANY, OF DETROIT, MICHIGAN, A CORPORATION OF MICHIGAN

DESIGN FOR A RADIATOR SHELL

Application filed February 4, 1932. Serial No. 42,732. Term of patent 14 years.

To all whom it may concern:

Be it known that I, WERNER H. A. GUBITZ, a citizen of the United States, residing at Detroit, county of Wayne, State of Michigan, have invented a new, original, and ornamental Design for a Radiator Shell, of which the following is a specification, reference being had to the accompanying drawings, forming a part thereof, and in which:

Fig. 1 is a front elevational view of a radiator shell incorporating my new design;

Fig. 2 is a perspective view thereof.

I claim:

The ornamental design for a radiator shell, as shown.

In testimony whereof I affix my signature.

WERNER H. A. GUBITZ.
